BAFFLE SYSTEM FOR STIRLING BOILERS.

1,132,015.

Specification of Letters Patent. Patented Mar. 16, 1915.

Application filed August 12, 1913. Serial No. 784,314.

To all whom it may concern:

Be it known that I, DAVID S. JACOBUS, a citizen of the United States, residing at Jersey City, in the county of Hudson and State of New Jersey, have invented new and useful Improvements in Baffle Systems for Stirling Boilers, of which the following is a specification.

My invention relates to a system of special baffles for Stirling boilers, and will be understood by reference to the accompanying drawing, showing a side elevation, partly in section, of one embodiment thereof.

In the design shown, the numeral 1 designates the front wall and 2, the rear wall of the boiler setting; 3 the furnace having a Roney stoker, although the furnace may be equipped with a chain-grate or other suitable form of stoker; and 4, 5 and 6 transverse steam and water drums, set parallel, and connected to a mud drum 7, by banks of water tubes 8, 9 and 10 respectively, the tubes being so curved as to enter the tube sheets radially. The steam space of the center drum is interconnected to both the front and rear drums by rows of curved steam circulating tubes 11, and to the water space of the front drum by rows of water circulating tubes 12, and to the water space 25 of the rear drum by rows of water circulating tubes 13. Coverings of fire brick 12' and 13', resting upon the upper row of tubes 12 and the row of tubes 13, respectively, prevent the gases passing above these tubes. A 30 feed pipe enters the rear steam and water drum 6, and the main steam outlet 5' is placed on top of the center drum. A superheater 14, of standard design, may be placed in the space between the front and middle 35 banks of tubes, the steam main being connected to one of the superheater boxes.

In the standard Stirling boiler a baffle rests against the rear tubes of the front bank, reaching from the mud drum nearly 45 to the top of the bank, and a second baffle rests against the rear tubes of the middle bank, reaching from the center steam and water drum nearly to the bottom of the bank. Shelves are placed near the top of the 50 front baffle and near the top of the rear bank of tubes. The baffles guide the gases up the front bank of tubes, down the middle bank, and up the rear bank to the outlet flue, the shelf near the top of the 55 rear bank preventing by-passing of the

gases between the tubes and the rear wall of the boiler setting.

To increase the heat transfer rate and the efficiency of the boiler, I have provided the following system of baffling: The furnace shown has an ignition arch 15, and a bridge wall 16. Supported upon the bridge wall is a vertical wall 17 extending upward to the first row of tubes of the front bank, and from one side wall of the setting to the other side wall. From the top of wall 17 a baffle 18 extends toward the top of the front bank of tubes, causing the gases to enter the front bank at the upper part thereof and to then flow downward over the tubes of the front bank at the rear of baffle 18 and wall 17. The tubes of the middle bank support two baffles, one of which, 19, is supported between the first and second rows and extends from the center steam and water drum downward to nearly the bottom of the bank, and the other, 20, is supported on the rear row of tubes and extends from the mud drum 7 upwardly to nearly the top of the bank. To cause the gases to flow 30 downward over the tubes of the rear bank, I introduce a baffle 21, extending from the rear steam and water drum 6 downward to nearly the bottom of the bank. The baffle 21 is at the rear of the bank 10 so as to expose, if desired, one or two rows of tubes in the last pass. The rear wall 2 of the setting is set far enough away from the lower part of the rear bank of tubes to allow a proper opening for the flow of the 35 gases. As indicated by the arrows, the gases from the furnace are first directed to the top of the front bank of tubes, thence into the superheater space and downward under the tubes of the front bank at the rear of wall 17 and baffle 18, then upward over the tubes of the middle bank, downward over the tubes of the rear bank, and finally upward through the idle pass back of the rear bank to the flue outlet 22.

With a baffle of the standard Stirling type, the hot gases pass over all of the surface of the tubes of the front bank before they reach the rear of the front bank. Where a special baffle is used on the front bank which cuts off any part of the front bank of tubes from the direct action of the furnace gases the temperature of the gases at the rear of the front bank will be higher than with the standard baffle. With such 105

special baffle the flame or hot gas will be projected into the space at the rear and near the top of the first pass; and, if there is any leakage through the baffle 19, which projects downwardly from the center steam and water drum, this flame or hot gas will play against the rear steam and water drum. The purpose, therefore, of using the additional water circulating tubes 13 is to avoid 10 the possibility of overheating the rear steam and water drum when the boiler is run at a high overload with special baffles of the kind described. The water level in the rear drum of a Stirling boiler when run at high over- 15 loads is lower than in the other steam and water drums and by providing the circulating tubes 13, water will continuously flow through said tubes from the middle steam and water drum and will cool the shell of 20 the rear drum. Without such circulators, the shell may become overheated if the flames or hot gases impinge upon it.

In my application Serial No. 784,313 filed 25 of even date herewith I have shown and described a Stirling boiler in which instead of a vertical wall at the rear of the combustion chamber and a baffle extending from said wall, a baffle extends upward from the mud drum at the front of the first bank of tubes 30 and constitutes the back of the combustion chamber. The vertical wall 17 provides for a dust collecting chamber as described more fully in my application Serial No. 777,503, filed July 5, 1913.

35 What I claim is:

1. A boiler of the class described comprising transverse steam and water drums and a mud drum, banks of tubes expanded into said drums, a wall at the rear of the 40 furnace chamber reaching upwardly to the front bank of tubes, a baffle extending from said wall to cause the gases to enter the front bank of tubes at the upper portion thereof and then to flow downwardly over said bank 45 at the rear of the baffle and wall, baffles in the middle bank one of which extends downwardly from the middle steam and water drum and the other upwardly from the mud drum to cause the gases to flow upwardly 50 over the tubes of the middle bank, a baffle in the rear bank extending downwardly from the rear steam and water drum to

cause the gases to flow downwardly over the tubes of the rear bank and then upwardly to the flue outlet back of the rear bank of tubes, 55 and water circulating tubes between the middle and rear steam and water drums.

2. A boiler of the class described comprising transverse steam and water drums and a mud drum, banks of tubes expanded 60 into said drums, a furnace, a secondary combustion chamber between the first and second banks of tubes, a wall at the rear of the furnace chamber extending upward to the first bank to cause the gases to first enter 65 said bank at the upper part thereof and to cross into said secondary combustion chamber, baffles to define the path followed by the gases passing from one bank to the next and to cause the gases to enter the last bank 70 at the upper part thereof and to flow downward among the tubes of said bank to the lower part thereof and upward at the rear of said bank, and water circulating tubes between the middle and rear steam and 75 water drums.

3. A boiler of the class described comprising transverse steam and water drums and a mud drum, banks of tubes expanded 80 into said drums, a furnace, a secondary combustion chamber between the first and second banks of tubes, a wall at the rear of the furnace chamber extending upward to the first bank to cause the gases to first enter said bank at the upper part thereof and to cross 85 into said secondary combustion chamber, a superheater located in said secondary combustion chamber, baffles to define the path followed by the gases passing from one bank to the next and to cause the gases to enter 90 the last bank at the upper part thereof and to flow downward among the tubes of said bank to the lower part thereof and upward at the rear of said bank, and water circulating tubes between the middle and rear 95 steam and water drums.

In witness whereof I have subscribed my name in the presence of two attesting witnesses,

DAVID S. JACOBUS.
